US00D717439S

(12) **United States Design Patent**
Noguchi et al.

(10) **Patent No.:** US D717,439 S
(45) **Date of Patent:** ** Nov. 11, 2014

(54) **SPHYGMOMANOMETER**

(71) **Applicants:** **So Noguchi**, Hirakata (JP); **Shuji Tsuruta**, Ibaraki (JP); **Yoshikazu Inami**, Akashi (JP); **Daisuki Nozaki**, Kyoto (JP); **Takeyasu Hashimoto**, Kusatsu (JP); **Shinjiro Komizo**, Kyoto (JP)

(72) **Inventors:** **So Noguchi**, Hirakata (JP); **Shuji Tsuruta**, Ibaraki (JP); **Yoshikazu Inami**, Akashi (JP); **Daisuki Nozaki**, Kyoto (JP); **Takeyasu Hashimoto**, Kusatsu (JP); **Shinjiro Komizo**, Kyoto (JP)

(73) **Assignee:** **Omron Healthcare Co., Ltd.**, Kyoto (JP)

(**) **Term:** **14 Years**

(21) **Appl. No.:** **29/447,376**

(22) **Filed:** **Mar. 2, 2013**
